BERNARD A. MALKIN, OF LACHINE, QUEBEC, CANADA.

DRIVING MECHANISM FOR PAPER-DRYING MACHINES.

Application filed May 22, 1926. Serial No. 110,927.

This invention relates to new and useful improvements in driving mechanism for paper drying machines and the like, and in particular to machines where two rows of 5 rolls are used one above the other, and in which an endless felt is used on the top rolls and a similar felt used on the bottom rolls, and the object of the invention is to provide a mechanism which will drive adjacent 10 upper and lower rolls uniformly to prevent the paper from breaking while passing between an upper and a lower roll, or at any point in its progress through the machine.

I am aware that individual motors have 15 been proposed to drive each roll, but this has not been satisfactory as the drier felts are depended upon to hold the surface speed of the drier rolls uniform, a condition which it is impossible to obtain in the individual 20 motor drives for machines using separate upper and lower felts as the following reasons will disclose. The felts absorb moisture from the wet sheet of paper and stretch and when said felts dry, they shrink. 25 It will be readily seen that when two separate felts are used that it is an impossibility to arrange a machine in which the stretching and shrinking of both felts will be uniform, so that the felts cannot be relied upon 30 to carry the sheet at the same surface speed through the drier sufficiently close to avoid breaking the paper.

In my invention I overcome the above difficulties by using a single motor for driving 35 one upper and one lower roll, so that the surface speed of the felts may be more uniform and independent of the stretching or shrinking of the felt. Each motor may be coupled up to drive an adjacent upper 40 and lower roll by any of the well known mechanical means, such as spur gear drives, bevel gear drives, worm gear drives, or a combination of any of the aforementioned gears.

45 In the drawings which illustrate various forms of my invention;

Figure 1 is a part side elevation of a paper drying machine with each motor driving one upper and one lower roll through 50 the medium of bevel gearing.

Figure 2 is a part end elevation of the device shown in Figure 1.

Figure 3 is a part side elevation of a paper drying machine with each motor driv-

ing one upper and one lower roll through 55 the medium of spur gearing.

Figure 4 is a part end elevation of the device shown in Figure 3.

Figure 5 is a part side elevation of a paper drying machine with each motor driving 60 one upper and one lower roll through the medium of worm and worm gearing.

Figure 6 is a part end elevation of the device shown in Figure 5.

Referring more particularly to the drawings, 11 designates the frame of the machine in which are rotatably mounted on suitable bearings, the upper rolls 12, the lower rolls 13, the guide rolls 14 and 15. The upper felt 12* which is of the endless type passes 70 around the lowermost surface of the guide rolls 14 and over the upper surfaces of the drier rolls 12. The lower felt 13* passes over the upper side of the guide rolls 15 and the lower side of the drier rolls 13. 75 The drier rolls are secured to suitable spindles 16 and 17, which may extend beyond the side of the frame for the purpose hereinafter stated. The paper sheet 18 is led alternately over one upper and under one 80 lower roll in its passage through the machine and is positioned so that it will come between the felt and the surface of the rolls. The passage of the paper is indicated by the arrow X. The above description applies 85 generally to all figures shown in the drawings, as this type of machine is well known in this art. My invention lies in providing a single motor for every pair of rolls in the machine, that is the motor is adapted to 90 drive one upper and one lower roll in unison to assist in maintaining the surface speeds of the felts uniform.

Referring to Figure 1, the motor 21 is mounted on a suitable surface 22 formed in 95 the frame and is shown positioned midway or approximately so between the centres of the upper roll 12 and the lower roll 13. The armature shaft 23 of the motor extends outwardly from each end of the motor and 100 secured thereto by any suitable means, such as the couplings 24, are the shafts 25, rotatably mounted in bearings 26, and having secured to their ends the bevel toothed pinions 27, adapted to engage with the bevel toothed 105 wheels 28, secured to the extended portions of the spindles 16 and 17. The bearing 26, may form part of an oil tight casing

29 surrounding the bevel wheels so that the wheels may be run in an oil bath during operation of the machine.

In Figures 3 and 4, the motor 21^a is mounted on a suitably fixed bed plate 30, and secured to the armature shaft 23^a of said motor is the toothed pinion 31 which is adapted to mesh with a tooth wheel 32 secured to the extension of the spindle 17. 10 As the spindle 16 has to rotate in the opposite direction to the spindle 17, the pinion 31 also meshes with a toothed idler wheel 33 which in turn meshes with a toothed wheel 34 similar to the wheel 32, so that 15 the rolls secured to the spindles 16 and 17 will move at uniform speed but in opposite directions of rotation to carry the paper through the machine. The idler wheel may be secured to a shaft 35 rotatably mounted 20 in suitable bearings formed in oil-tight castings 36, surrounding the pinion idler and toothed gear wheels 34 and 32, so that they may be properly lubricated during the operation of the machine. In Figure 5, the 25 motor 21^b is mounted on a suitable surface 22^a formed in the frame of the machine, and is coupled in any suitable manner to an angularly disposed shaft 37 which may be built in sections suitably coupled together. 30 Secured to or formed with sections of the shaft 37, are the worms 38 and 39, which engage with worm wheels 40 and 41 secured to the spindles 15 and 16. The worm 38 may be made with a right hand thread and 35 the worm 39 with a left hand thread or vice-versa, to ensure that the rolls will turn in opposite directions. The foregoing description is only illustrative of some types of gearing which may be employed for driving 40 one upper and one lower drier roll by means of a single motor, and it will be readily seen that many modifications may be made in the types or trains of gears employed to transmit motion between the motor 21 and the drier roll spindles, all of which 45 are within the scope of my invention.

By using a single motor for each pair of drier rolls, that is one top and one bottom, the surface speed of the felts are kept at 50 practically the same speeds, thereby eliminating any tendency for the paper sheet to break through being altered from one speed to another as it passes through the machine alternately from one upper to one lower roll, a condition which exists when a single 55 motor is used for each drier roll. It also ensures the same surface speeds of the felts even though their tendency to stretch or shrink differ from one roll to another, as 60 the motor forms a balancing as well as a driving means between the said upper and lower rolls.

Even though I have not shown any electrical controlling means for the separate 65 motors, it will be readily understood that

said motors may be connected electrically to run independently of one another, or they may be connected to a common controlling device.

Having thus described my invention, what 70 I claim is:—

1. In a paper making machine having a frame end and a plurality of upper and lower rolls rotatably mounted therein, a plurality of motors, each motor being connected 75 to drive only one upper and one lower roll in unison through suitable roll driving means.

2. In a paper making machine, a frame, a plurality of upper drier rolls rotatably mounted in the frame, a plurality of lower drier rolls, an upper endless felt, and guide rolls therefor, a lower endless felt and guide rolls therefor, said felts being adapted to pass over their respective drier and guide 80 rolls, and a plurality of motors, each motor being adapted to rotate an upper and a lower roll in unison through suitable driving means.

3. In a paper making machine, a frame, a plurality of upper drier rolls rotatably mounted in the frame, a plurality of guide rolls rotatably mounted in the frame and positioned between the upper drier rolls, a plurality of lower drier rolls rotatably 90 mounted in the frame and guide rolls between each pair of lower rolls, an endless upper felt passing over the upper drier rolls and under the guide rolls, an endless felt passing under the lower drier rolls and over 95 the lower guide rolls, a plurality of driving units each unit being independent of the other and adapted to drive one upper and one lower roll in unison. 100

4. In a paper making machine, a frame, 105 having parallel rows of drier rolls rotatably mounted therein, a plurality of independent driving units each connected to drive only one roll in each row of rolls, the connection being such as to operate the different rolls 110 in unison.

5. In a paper making machine, a frame, having two parallel horizontal rows of drier rolls rotatably mounted therein, a plurality 115 of independently controlled driving units, each unit being adapted to drive two rolls, one in each row of drier rolls.

6. In a paper making machine, a frame having two parallel horizontal rows of drier rolls rotatably mounted therein and arranged in zig-zag manner from end to end of the machine, guide rolls between each pair of upper and each pair of lower rolls, and an endless felt passing over the upper drier rolls and under the guide rolls therebetween, endless felt passing under the lower drier rolls and over the guide rolls therebetween, angularly inclined means connecting each of the upper drier rolls and the lower drier roll adjacent thereto, and inde- 125 130

pendently operated means for driving each ing each upper roll with one lower roll, and of the last mentioned means.

7. In a paper making machine, a frame having two parallel horizontal rows of drier rolls rotatably mounted therein and arranged in zig-zag fashion from end to end of the machine, mechanical means connect-

independently electrically operated means for operating each of the aforesaid mechanical means.

In witness whereof, I have hereunto set

BERNARD A. MALKIN.
